(57) **CLAIM**

The ornamental design for a shower tap, as shown and described.

DESCRIPTION

FIG. 1 is a perspective view of a shower tap according to the present invention.

FIG. 2 is a bottom plan view of the shower tap illustrated in FIG. 1.

FIG. 3 is a top plan view of the shower tap illustrated in FIG. 1.

FIG. 4 is a left side elevation view of the shower tap illustrated in FIG. 1.

FIG. 5 is a right side elevation view of the shower tap illustrated in FIG. 1.

FIG. 6 is a front elevation view of the shower tap illustrated in FIG. 1; and,

FIG. 7 is a rear elevation view of the shower tap illustrated in FIG. 1.

The broken line showing in FIG. 7 is included for the purpose of illustrating portions of the shower tap and forms no part of the claimed design.
